CUTTER MOUNTING

Fred. C. Smith, Jr., Houston, Tex., assignor to
 Hughes Tool Company, Houston, Tex., a corporation of Delaware

Application February 25, 1937, Serial No. 127,578

8 Claims. (Cl. 255—73)

The invention relates to cutters such as are employed upon reamers designed for use in deep well drilling.

The invention pertains more particularly to the means for mounting and supporting the cutter in the head of the reamer and has for its object the formation of a supporting block for the ends of the cutter pin which may be easily and quickly applied and locked.

I aim to provide a mounting for the cutter pin which is of simple and strong construction and easily secured in place so that it will not become loosened.

The invention resides particularly in the construction of the supporting block and its means of attachment in supporting position in the reamer head.

In the drawing herewith Fig. 1 is a side view of a broken section of the reamer head showing the cutter mounted therein by the use of my invention.

Fig. 2 is a transverse section on the plane 2—2 of Fig. 1.

Fig. 3 is a perspective view of the supporting block.

Fig. 4 is a perspective view of the locking plate.

The head of the reamer may be of any desired construction. I show a head 1 of generally cylindrical contour with outwardly projecting ribs or bosses 3 thereon spaced apart vertically to include the reamer cutters between them. I show supports for three cutters, as will be seen from Fig. 2, but a different number of cutters may be used.

Adjacent each cutter the body of the reamer is recessed somewhat at 4 to provide a pocket for the cutter 5. Each rib 3 is cut away above the pocket 4 to form a mortised recess 6 to receive the cutter supporting block 7.

The cutter is shown as approximately cylindrical but with its ends tapered as desired at 8 and 9 at the upper and lower ends respectively. Each end has thereon a bearing pin 10 to fit within a bearing opening 11 within the bearing block 7. The bearing blocks at each end are of the same construction.

In Fig. 3 one of the bearing blocks is shown detached. The recess 11 extends away from the cutter recess about half way through the block. The block is dovetailed longitudinally and tapered longitudinally to fit loosely within the mortised recess 6 of the head. As will be seen from Fig. 2, each block is narrower in width than the recess 6 to permit the wedge plate 12 to be introduced

into the recess beside the block and lock the block in place.

On the side of the block away from the wedge, the block has a transversely extending rib 13 to fit within a keyway or groove 14 in the side of 5 the recess 6, and there prevent longitudinal movement of the block in said recess.

The wedge plate, shown in Fig. 4, is wedge shaped both longitudinally and transversely. That is it tapers in thickness away from the end 10 15 and from the side 16. At the larger end the block has a locking arm 17 at approximately right angles thereto, said arm having an opening 18 therein to receive a cap screw 19, by means of which it is secured to the block 7. The double 15 wedge shape of the wedge plate enables the plate to wedge the block 7 rigidly into position with the ridge 13 thereon tightly fitting within the groove 14 in the recess 6 as will be seen in Fig. 1. It further tends to prevent the plate from being 20 moved outwardly from the mortised recess 6 as will be obvious from Fig. 2. The locking plate will be driven into the position shown in Fig. 1 and then fixed in that position by the cap screw 19.

It will be clear that before the cutter 5 is placed in its recess 4, the supporting blocks 7 may be slipped over the ends of the pins 10 and the whole assembly moved as a unit into position ready to receive the wedges. The wedge plates 30 will then be driven in place to force the blocks into rigid engagement with the walls of the recesses 6 and the ridges 13 thereon fitted within the grooves 14. The cap screws 19 fix the wedge plates to the supporting blocks 7. A lock washer 35 20 may be used to prevent release of the cap screw. The wedge plate engages against the tapered side of the block 7 and a very tight fit of the assembled block and wedge in the recess 6 is thus obtained.

It will be noted that this assembly is very easily and quickly made. The parts are simple and economical to manufacture and may be replaced when worn without appreciable loss of time or materials. To remove the blocks, it is only necessary to unscrew the cap screws and by engaging a drift pin or wedge under the arm 17 of the wedge plate, the wedge may be removed. The block will then drop free and may be removed.

What I claim as new is:

1. A reamer body having a plurality of cutter pockets therein, a reamer cutter in each pocket, a mortised recess at each end of each of said pockets, one side of each recess having a transverse groove, a bearing pin at each end of each 55

- cutter, a bearing block to receive said pin, said block being mortised to fit loosely in said recess, a ridge thereon to engage said groove, and a longitudinally tapered wedge plate formed to engage the side of said block opposite said ridge and within said recess to wedge said block in position. 5
2. A reamer body having a plurality of cutter pockets therein, a reamer cutter in each pocket, a mortised recess at each end of each of said 10 pockets, one side of each recess having a transverse groove, a bearing pin at each end of each cutter, a bearing block to receive said pin, said block being mortised to fit loosely in said recess, a ridge thereon to engage said groove, and a longitudinally tapered wedge plate formed to engage 15 the side of said block opposite said ridge and within said recess to wedge said block in position and means on said plate engaging said block to hold said plate in wedging position. 20
3. A reamer body having a plurality of cutter pockets therein, a reamer cutter in each pocket, a mortised recess at each end of each of said 25 pockets, one side of each recess having a transverse groove, a bearing pin at each end of each cutter, a bearing block to receive said pin, said block being mortised to fit loosely in said recess, a ridge thereon to engage said groove, and a longitudinally tapered wedge plate formed to engage 30 the side of said block opposite said ridge and within said recess to wedge said block in position, a laterally extending arm on the larger end of said wedge plate, and a screw to secure said arm to said block. 35
4. A reamer body having a cutter receiving pocket, bearing block receiving recesses at the upper and lower ends of said pocket, bearing blocks in said recesses, a cutter in said pocket, bearing pins at each end of said cutters to engage within bearing openings in said blocks, means at 40 one side of each block intermediate its ends interengaging with the side wall of its recess to prevent longitudinal movement of the block in the recess, and means to force said block laterally 45
- in said recess to hold said interengaging means securely against disengagement. 5
5. A quadrangular bearing block having a bearing recess therein for a cutter axis, said block being formed with an inner side wider than the opposite outer side to fit a mortised recess, the other sides between the outer and inner sides being formed, one with a transverse ridge thereon and the other side formed to taper longitudinally of the block to interfit with a wedge shaped plate. 10
6. A quadrangular bearing block having a bearing recess therein for a cutter axis, said block being formed with an inner side wider than the opposite outer side to fit a mortised recess, the other sides between the outer and inner sides being formed, one with a transverse ridge thereon and the other side formed to taper longitudinally of the block to interfit with a wedge shaped plate and a cap screw engaging with said block at the end opposite said bearing recess. 15
7. A reamer body, a cutter mounted thereon, longitudinally extending bearing projections on said cutter, a mortised recess in said body at each end of said cutter, a dovetailed bearing block in each recess having a bearing socket to receive 20 one of said projections, said block being tapered on one side, a projection on the opposite side engaging the wall of said recess, and a wedge plate to fit within said recess on the tapered side of said block and hold said projection in said wall. 25
8. A reamer body, upper and lower projections thereon, said projections having longitudinally mortised recesses therein, a cutter between said recesses, supporting blocks at each end of said cutter in said recesses, means to support said cutter rotatably relative to said blocks, interengaging means between one side of each of said blocks and the wall of its recess, and a wedge to engage between said block and the opposite wall 40 of said recess and force said interengaging means into locking position. 45
